PARALLEL COMPRESSION TAP

John J. Klosin, New Brunswick, N.J., assignor to The Thomas & Betts Co., Elizabeth, N.J., a corporation of New Jersey

Application March 6, 1959, Serial No. 54,874

Term of patent 14 years

(Cl. D26—1)

Fig. 1

Fig. 2

Fig. 3

Fig. 1 is a perspective view of a parallel compression tap, showing my new design;

Fig. 2 is a side elevational view, partly in cross-section, to a reduced scale; and

Fig. 3 is an end elevational view thereof, to a reduced scale.

The opposite sides and end faces of the parallel compression tap not shown are substantially mirror images of those shown.

I claim:

The ornamental design for a parallel compression tap, as shown and described.
